COMBINED FORM SPREADER AND TIE

Filed May 24, 1930

Fig. 1

UNITED STATES PATENT OFFICE

SAMUEL C. AWBREY, OF KANSAS CITY, MISSOURI, ASSIGNOR TO ETHEL AWBREY, OF
KANSAS CITY, MISSOURI

COMBINED FORM SPREADER AND TIE

Application filed May 24, 1930. Serial No. 455,331.

This invention relates to concrete forms and has particular reference to a tie and spreader member which is adapted to maintain the walls of the form in their properly spaced relation during the building of the same and while the concrete is being poured.

It is known in this art that form ties and spreaders must present strength enough to maintain the form walls in proper relative position, yet must be designed to permit of quick removal of the form walls after the concrete has set. There is always a projected head which must be entirely removed or broken away from the body portion of the tie and spreader and it is an object of this invention to provide a form of construction which will permit of quick and easy removal of the head.

The primary object of this invention is to provide a form tie and spreader which is inexpensive to manufacture, efficient in its operation and unlikely to cause injury to the concrete wall through the attraction of moisture after the same has served its purpose as a support for the form used in pouring the wall.

Another object of this invention is the provision of a new article of manufacture especially adapted for use as a form tie and spreader that is provided with a plurality of key engaging slots, one of which slots extends inwardly to terminate in a transverse opening which serves as a trap for water or moisture and precludes the same from entering the wall further than said opening which is filled with concrete when the wall is poured.

Another object of the invention is the contemplation of a tie and form spreader having a head at each end thereof provided with a corner notch which permits of cutting the tie from material with the ends of adjacent ties in overlapped relation.

An even further object of the invention is the provision of a tie and spreader for concrete forms which is maintained in combination therewith through the use of a novelly constructed specially formed key which presents a form engaging edge of equal effect

when the same is inserted into position from either end thereof.

Since the structural details of this invention constitute a majority of the novel features thereof, further objects will not be set forth at this point, but will be made clear throughout the detailed specification referring to the accompanying drawing wherein

Figure 1 is a perspective view of a form tie and spreader embodying the novel features contemplated by this invention.

Fig. 2 is a reduced fragmentary vertical section through the opposing walls of a concrete form showing the tie and spreader in the operative position.

Fig. 3 is an enlarged fragmentary detailed view along the face of one end of the tie and spreader, key removed.

Fig. 4 is a perspective view of the specially formed key which may be used with the tie and spreader.

Fig. 5 is a fragmentary vertical cross section through the tie and spreader positioned with the wall form, and,

Fig. 6 is a fragmentary view of one end of a modified form of the tie and spreader.

Like reference characters refer to similar parts throughout the several views and the numeral 8 indicates the walls of a concrete form which are built up of boards and which must be maintained in the properly spaced relation. Concrete 10 is poured between walls 8, allowed to set, after which walls 8 are removed.

The tie and spreader made in accordance with this invention may include an elongated plate 12 which is divided into three distinct portions. The body 14 is stiffened through the use of an embossed rib or bead 16 which extends longitudinally of plate 12 along the body portion 14 thereof. At each end of the plate 12 is formed a wall engaging head 18 which is connected to body 14 by the neck 20. A pair of spaced apart lugs 22 are struck from plate 12 and projected therefrom in a plane extending transversely to the plate to opposite sides thereof as shown in the drawing. Striking lugs 22 from plates 12 creates the neck 20 which should be formed as clearly shown in Fig. 3 with its outer edges

converging as the head 18 is approached. Thus neck 20 will be narrower at the end joined by head 18 than where it is joined by body 14. Lugs 22 project substantially perpendicular to plate 12 and, obviously, their inner edges will be angled in conformity with the angle of convergency of neck 20. Lugs 22 are disposed in substantially the same plane and bear against the inner sides of walls 8 when the tie and spreader is in position.

A centrally positioned longitudinally extending slot 24 is formed in plate 12 to extend across neck 20 and into head and body 18 and 14 respectively. This slot 24 intersects the plane of lugs 22 and terminates in communication with transverse slot 26 which may be arcuate as illustrated in the drawing and which should project toward the opposite edges of plate 14 to terminate beyond the adjacent edges of lugs 22. When the tie and spreader is in position the end of slot 24 lying in head 18 is beyond the outer surface of the wall 8 to permit insertion of the hereinafter described key. A hole 28 should be pierced in the position shown to receive a nail or similar fastening means not here shown when the tie and spreader is positioned at the top of the form walls 8.

A slot 30 formed in head 18 between one edge thereof and slot 24, yet not in overlapped relation therewith, allows the tie and spreader to be used with forms having walls of various thicknesses. A corner notch 32 is cut into the head 18 to extend inwardly thereof from its end and one side to a point beyond slot 30. An angled side 34 of corner notch 32 intersects lines projected longitudinally from the central slot 24 and meets the transverse edge 36 of corner notch 32 as illustrated in Fig. 3. It is notable that the adjacent ends of slot 24 and 30 and the edge 36 of corner notch 32 all lie in substantially the same plane which extends transversely of the head 18. The corner notch 32 at one end of plate 12 is diagonally opposite the corner notch 32 formed in the other end thereof. Thus when the tie and spreader is being manufactured from stock of constant width there is an overlap which presents an appreciable saving in a manner which in no way affects the efficiency and strength of the device.

In combining the tie and spreader above described with the concrete form having walls 8, it is desirable to provide a quickly positioned key 38 which may be made as shown in Fig. 4. The edge 40 of key 38 lies in a straight continuous plane to rest against the outer face of the form wall 8. A shoulder 42 formed on the opposite edge of key 38 intermediate the ends thereof presents a stop and the edge 44 converges toward the two ends of the key 38 respectively as they are approached from shoulder 42. Thus, a perfectly balanced key is made and the workman

need not lose time by concerning himself as to which end should enter slot 24 or 30 as the case may be. Likewise, key 38 may be efficiently cut from stock without waste.

The faces of the concrete wall 10 should be smooth after the form has been removed. Walls 8 are loosened merely by dislodging keys 38, which may be used again, and when walls 8 have been removed the heads 18 are broken away by severing the plate 14 at the narrowest part of neck 20.

The advantage of the construction described is obvious. The relation of slots and lugs renders the breaking off of the head 18 exceptionally easy and since the lugs 22 come off with head 18, it is plain to be seen that the only portion of the plate 14 forming the tie and spreader that is exposed is the ends of the two portions forming the neck 20. As shown in Fig. 3, lugs 22 form cavities in the wall 10 after the concrete has set which, after the lugs and head have been removed, may be filled with concrete to seal the wall and render it impervious to moisture. The transverse slot 26 and a portion of slot 24 is filled with concrete when the wall is being poured and in the event moisture attempts to work a way inwardly or outwardly along the plate left therein, it will be trapped by the various off-sets presented at the end of the plate embedded in the concrete wall 10.

Manifestly, the tie and spreader shown and described is susceptible of being formed in many ways. For example, the modification shown in Fig. 6 might be followed. The only difference between the preferred and this modified form being that the lugs 22 are struck from the plate 14 to communicate directly with the sides of longitudinal slot 24 rather than to lie adjacent to the edges of the device. The portion to be severed when removing the head remains the same size and the efficiency of the tie and spreader is not changed.

Having thus described the invention, what is claimed as new and desired to be secured by Letters Patent is:

1. A form tie and spreader comprising an elongated plate, a plurality of spaced-apart lugs projecting from the plate in a plane transverse to the same, a longitudinal slot formed through the plate intersecting the plane of said lugs and a transverse slot through the plate at the inner end of the longitudinal slot and joined thereby.

2. A form tie and spreader comprising an elongated plate, a pair of spaced-apart lugs projecting from the plate in a plane transverse to the same adjacent each end respectively thereof, a longitudinal slot formed through the plate extending between said lugs and intersecting the plane thereof and a transverse slot through the plate at the inner end of the longitudinal slot, joined thereby and extending outwardly therefrom toward

the edges of the plate to points beyond the adjacent edges of said lugs.

3. A form tie and spreader comprising an elongated plate having a wall engaging head at each end thereof joined by a ribbed body, a neck between each head and the body respectively, a central longitudinal slot formed through the plate and across the neck and extending into the head and body of the plate and an arcuate transverse slot formed through said plate and joined by the longitudinal slot at its inner end.

4. A form tie and spreader comprising an elongated plate having a wall engaging head at each end thereof joined by a ribbed body, a pair of oppositely disposed lugs projecting in a plane transverse to the plate, a neck between each head and the body respectively, said neck converging as the head is approached and having its narrowest portion between said lugs, a longitudinal slot formed through said plate and across the neck and extending into the head and body of the plate and a transverse slot joined by the longitudinal slot at its inner end.

In testimony whereof, I hereunto affix my signature.

SAMUEL C. AWBREY.
